UNITED STATES PATENT OFFICE

EDWIN S. GEORGE AND HAROLD L. BLYDENBURGH, OF DETROIT, MICHIGAN; SAID BLYDENBURGH ASSIGNOR TO SAID GEORGE

DESIGN FOR A HOUSING FOR AIR CONDITIONING APPARATUS

Application filed December 19, 1932. Serial No. 46,530. Term of patent 3½ years.

To all whom it may concern:

Be it known that we, EDWIN S. GEORGE and HAROLD L. BLYDENBURGH, citizens of the United States, residing at Detroit, in the county of Wayne and State of Michigan, have invented a new, original, and ornamental Design for a Housing for Air Conditioning Apparatus, of which the following is a specification, reference being had to the accompanying drawing, forming part thereof.

Fig. 1 is a plan view of a housing for air conditioning apparatus, showing our new design, and

Fig. 2 is a vertical elevation thereof.

We claim:

The ornamental design for a housing for air conditioning apparatus, as shown.

EDWIN S. GEORGE.
HAROLD L. BLYDENBURGH.
